AIR CONDITIONING APPARATUS

Max Crandall and Marsh Sanders, Kingfisher,
Okla.

Application May 31, 1938, Serial No. 211,069

2 Claims. (Cl. 261—92)

This invention relates to air conditioning apparatus, and has particular reference to improvements in air conditioning apparatus of the general type comprising a casing, means for circulating air therethrough, and means within said casing for moistening the air during its circulation therethrough.

According to the invention, the casing of the apparatus is provided with a water compartment, the air is circulated through the casing above water contained in said compartment, a moisture carrier unit having passageways therethrough is rotatably mounted in the casing in a position to have its lower portion immersed in water contained in the water compartment and to have the air pass through the passageways in the upper portion thereof, and vanes are provided on said unit whereby air circulated through the casing causes said unit to rotate. Thus, the upper portion of the moisture carrier unit, with which the circulated air contacts, is maintained wet so as to wet the circulated air and, to a considerable extent, to remove therefrom dust and other foreign matter which may be suspended therein. The moisture carrier is rotatable on a horizontal axis and may comprise either a set of disks spaced apart along a shaft extending transversely relative to the direction of the air flow, or a set of concentric, hollow cylinders mounted on a shaft extending in the same direction as the air flow. In either case, a special object of the invention is to provide said disks, or cylinders, as the case may be, with vanes extending into the passageways therebetween to be acted upon by the circulated air to cause the moisture carrier unit to be rotated, and to shape said vanes so that, within their lengths, they do not completely obstruct said passageways against flow of air therethrough, but, on the contrary, permit flow of air substantially throughout all portions of said passageways.

Another special object of the invention, both from a practical, economical manufacturing standpoint, and from a utilitarian standpoint, is to form the vanes by bending them from the disks or cylinders comprising the moisture carrier unit, openings thereby being provided in said elements adjacent to the vanes through which some of the circulated air may flow from one to another of the passageways for most effective moisture treatment.

The present apparatus may be constructed for use in motor vehicles as well as in the form of a fixed or portable unit for room air conditioning purposes. If it is used in a motor vehicle the

water may tend to surge due to various different movements of the vehicle. Accordingly, another special object of the invention is to provide practical means to limit such surging.

With the foregoing and other objects in view, which will become more fully apparent as the nature of the invention is better understood, the same consists in the novel features of construction, combination and arrangement of parts as will be hereinafter more fully described, illustrated in the accompanying drawing and defined in the appended claims.

In the accompanying drawing, wherein like characters of reference denote corresponding parts in related views:

Figure 1 is a vertical section through a form of apparatus embodying features of the invention and constructed particularly for use in motor vehicles, air craft, watercraft or the like.

Figure 2 is a horizontal section on the line 2—2 of Fig. 1.

Figure 3 is a perspective view of one of the disks included in the moisture carrier unit.

Referring to the drawing in detail, first with reference to the particular form of the invention illustrated in Figs. 1 to 3, A designates, generally, a rectangular casing which may be formed from any suitable material into any desired height, width and length and which is composed of side walls 10, 10, end walls 11, 11, a bottom wall 12 and a removable cover 13.

Extending from one of the side walls 10 and communicating with the casing through an opening in said side wall, is an air inlet duct 14, while extending from the other of said side walls and communicating through an opening therein with the casing, is an air outlet duct 15.

The duct 14 is provided with a branch 16, and within said duct is a valve 17 which may be swung to close said duct outwardly of said branch and to simultaneously open the latter, or to close said branch and to simultaneously open said duct outwardly of said branch. The branch 16 is open to the atmosphere and the duct 14 may, if desired, be connected with a heating device. Thus, by positioning the valve 17 so that it closes the duct 14 outwardly of the branch 16 and opens the latter, air at atmospheric temperature may be admitted to the casing. On the other hand, by positioning the valve 17 so that it closes the branch 16 and opens the duct 14, heated air may be admitted to the casing.

In this connection it is pointed out that the apparatus illustrated in Fig. 1 is particularly designed for use in automobiles and that the duct 14 is intended for con-

nexion, if desired, with an air heating device, so that simply by manipulation of the valve 17 either atmospheric or heated air may be admitted to the apparatus.

5 In the duct 15 is mounted a motor driven fan 18 which, in operation, produces a flow of air from the duct 14 through the casing and outwardly from the casing through said duct 15, the air being caused to circulate beneath an ice compartment 19 in the upper portion of the casing because said ice compartment is interposed between said ducts and extends from end to end of the casing, and because the side wall of said ice compartment adjacent to the side wall of the casing 10 from which the duct 14 extends, reaches to said casing side wall above said duct.

Mounted within the casing below the ice compartment 19 is a moisture carrier unit designated generally as B. This unit extends substantially 20 from end to end of the casing and is composed of a plurality of disks 20 suitably mounted in spaced apart relationship along a shaft 21 which is horizontally disposed, transversely with respect to the direction of air flow through the casing, and 25 which may be journaled in any suitable manner for free rotation. For example, the ends of said shaft may be mounted in ball bearings 22 and said ball bearings may be supported by the bottom flanges of angle-iron members 23 fastened 30 to the end walls of the casing, tongues 24 being bent outwardly from the vertical flanges of said angle-iron members to hold the ball bearings against sidewise movements. The bearings 21 thus are self-aligning and the moisture carrier 35 unit thereby is very freely rotatable.

Extending laterally from each disk 20 is a series of any desired number of radially or substantially radially disposed vanes 25 which are spaced equal angular distances apart and which are of 40 triangular shape with their wider ends preferably disposed outwardly. Preferably, too, the outer ends of said vanes extend to the peripheries of the disks 20 and are of widths corresponding to the spaced apart relationship of said disks, 45 whereby they serve as spacing elements for the peripheral portions of said disks. In any event, said vanes are disposed in the passageways between the disks 20. Moreover, the vanes of the several disks are displaced preferably equal 50 amounts angularly and in the same direction. In other words, related vanes of the several disks are disposed spirally of the unit B. Accordingly, air flowing through the passageways between the upper portions of the disks 20 impinges against 55 the vanes 25 and produces rotation of the unit B.

The bottom portion of the casing A comprises a water compartment which may be filled through a filling opening 26 normally closed by a plug or cap 27 and which may be drained 60 through a drain opening 28 normally closed by a plug or cap 29.

The disks 20 of the moisture carrier unit B have their lower portions disposed to be immersed in water contained in the compartment B and 65 their upper portions disposed to remain above the level of water in said compartment B when water in said compartment is at its highestmost level. Moreover, the tops of the disks 20 are disposed closely adjacent to the bottom of the ice 70 compartment 19. Accordingly, substantially all air flowing through the casing is required to pass through the passageways between the disks 20, and in passing through said passageways it acts, as aforesaid, upon the vanes 25 to rotate said disks, thereby causing newly wetted portions of

the latter constantly to be brought uppermost. The air therefore constantly contacts with newly wetted portions of the disks and is moistened and, to a considerable extent, cleansed of foreign matter by reason of such matter being deposited in the water films on the disks 20. Moreover, if the water is cool it serves to cool the air, and, in any event, if ice is contained in the compartment 19 the air is cooled due to its contact with and flow beneath said compartment.

Due to the triangular shape of the vanes 25 air is permitted to flow through the passageways between the disks 20 substantially throughout the height of said passageways above the water level and to contact with substantially all portions of said disks above the water level, whereby it is most effectively moisture treated. Moreover, if, as shown, the vanes 25 are comprised by portions of the disks 20 bent from said disks, the disks inherently are provided with openings 30 of the same shape as said vanes adjacent to the latter, and the air may circulate through these openings between the passageways, whereby it is further most effectively moisture treated.

Assuming installation of the apparatus in an automobile or in any place where it may be tilted, it is apparent that water contained in the water compartment might, as a result of pronounced tilting of the apparatus, tend to surge undesirable amounts upwardly along the sides of the casing A. Accordingly, means are provided to limit such surging, said means comprising, in the present instance, baffle plates 31 hinged to the side walls of the casing at suitable points above the water level and having their lower ends free and provided with suitable floats 32. Under the influence of gravity the plates 31 normally assume substantially vertical positions in which they do not interfere in any way with flow of air through the casing, but when the water surges it acts on the floats 32 to swing the plates 31 outwardly above the water, whereby surging of the water is limited.

According to the preferred form of the invention holes are provided in the bottom of the ice compartment to permit cold water to drip from said compartment upon the elements comprising the moisture carrier unit and, in the case of the Figs. 1 to 3 form of the invention, through the passageways between said elements, whereby such water is effective to treat the air.

From the foregoing description considered in connection with the accompanying drawing it is believed that the construction, operation and advantages of the present apparatus will be readily apparent to those skilled in the art to which the invention appertains. It is desired to point out, however, that while only certain specific embodiments of the invention have been illustrated and described, the same manifestly is capable of various other specific embodiments within its spirit and scope as defined in the appended claims.

We claim:

1. Air conditioning apparatus comprising a casing having in the bottom thereof a water compartment open at its top, means for circulating air through said casing above water contained in said compartment, a moisture carrier unit comprising a series of elements spaced apart to provide a series of passageways therebetween and mounted in said casing for rotation about a horizontal axis with its lower portion disposed to be immersed in water contained in said compartment and its upper portion disposed to have the

circulated air pass through said passageways, means whereby said unit is caused to be rotated by air circulated through said casing, the side walls of the casing being spaced from the sides of said unit, and means to limit upward surging of the water between said side walls and the sides of said unit when the casing is tilted.

5 2. Apparatus as set forth in claim 1 in which

the means to limit surging of the water comprises plates free at their lower ends and pivoted at their upper ends to the side walls of the casing above the normal water level in the water compartment, and floats carried by said plates 5 at their free, lower ends.
